UNITED STATES PATENT OFFICE.

NATHANIEL P. SLATE, OF TANGENT, OREGON.

SCRAPER.

1,407,683.

Specification of Letters Patent. Patented Feb. 21, 1922.

Application filed June 5, 1920. Serial No. 386,893.

To all whom it may concern:

Be it known that I, NATHANIEL P. SLATE, a citizen of the United States, residing at Tangent, in the county of Linn and State of Oregon, have invented certain new and useful Improvements in Scrapers, of which the following is a specification.

This invention relates to excavating scrapers and seeks primarily to simplify the construction of such implements whereby the cost of manufacture will be reduced and the operation simplified. The invention also seeks to so construct a scraper that there will be no loss of efficiency and a load may be taken up, transported, and dumped with less labor than with similar devices heretofore produced, and the invention also has for its object the provision of a construction which will be strong and durable.

20 The invention is illustrated in the accompanying drawings, in which—

Figure 1 is a side elevation of a scraper embodying the improvements, the full lines showing the device in the position assumed 25 when taking up a load and the dotted lines showing the position when the load is being transported;

Fig. 2 is a similar view showing the manner of dumping a load;

30 Fig. 3 is a plan view;

Fig. 4 is a rear elevation;

Fig. 5 is an enlarged longitudinal section of a portion of the tongue;

Fig. 6 is a detail transverse section on the 35 line 6—6 of Fig. 5.

Figs. 7 and 8 are elevations showing another embodiment of the invention.

The scoop or scraper body may be conveniently formed of a single blank presenting a bottom plate 1, a back plate 2 and side wings 3, the back plate and the side wings being folded into upright positions relative to the bottom, and the side wings being of such length that their rear extremities will 45 present lips 4 which may be folded against the upturned back plate and riveted or otherwise rigidly secured thereto. To the back plate I secure spaced standards 5 which converge upwardly and are preferably 50 formed of angle bars, as shown, so that they will very effectually reinforce the back plate and prevent buckling of the same. These standards have their lower portions turned under the bottom of the scoop whereby they 55 will form runner extensions 6 and wooden runner bars 7 may be secured to the said run-

ner extensions to provide a broader bearing upon the ground and reduce the wear upon the metallic members. The front ends of the runner bars 7 and of the runner extensions 60 6 are, of course, beveled, as shown at 8, to more readily pass over the ground and also to facilitate the taking up of a load, as shown in Fig. 1 and as will be presently more particularly described. The lower forwardly 65 projecting extensions 6 of the standards 5 reinforce and prevent buckling of the bottom plate 1 of the scoop and constitute the main support therefor so that the said plate will not run directly upon the ground and 70 wear upon the same will be overcome so that the life of the scoop will be prolonged. As shown at 9, the standards 5 extend above the upper edge of the back plate 2 and are more sharply converged, the extremities being 75 turned into vertical planes and disposed parallel, as shown at 10, to receive between them the rear extremity of a tongue 11. The rear end of the tongue may be reinforced by a metallic strap 12, as shown, and it is pivotally held between the members 10 by a pivot bolt 13. The draft tongue is of the usual form and dimensions and is provided at its front extremity with a clevis 14 whereby it 80 may be coupled to a tractor.

To the front side of the back plate 2, at the ends and at or adjacent the upper edge thereof, I secure arms 15 which are preferably flat bars projecting forwardly from the back plate. These bars are provided with a plurality of openings therethrough and rockers 16 are secured to the said arms by bolts 17 inserted through suitable openings in the rocker members and aligned openings in the arms so that the combined length of 95 the arms and the rocker members may be adjusted to regulate the depth of the dirt spread when the scraper discharges. The forward ends or extremities of the rocker members 16 are curved downwardly and are 100 secured to the forward extremities of anchor bars or straps 18 which are adjustably secured to the sides 3 of the scoop by bolts 19 inserted through any one of a plurality of bolt openings in the side members 3 and 105 through registering openings in the anchor bars. Draft plates 20 are secured to the front extremities of the side members 3 and project forwardly beyond the same, the said draft plates being provided at their ends 110 with suitable openings to receive the hooks 21 at the rear ends of a draft bail 22 which

extends forwardly beneath the tongue and has its forward free end disposed between the tongue and a guide rod or bar 23 secured upon the under side of the tongue and extending longitudinally thereof. The front end of the bail is preferably provided with small projections or ears 24 which, by engaging the said rod 23, serve to prevent lateral movement of the bail and the scoop relative to the draft tongue. The pivot bolt 13 is thus relieved of some of the lateral strain imposed upon it and the scoop caused to travel in the direct line of draft. By reference to Figs. 1 and 2 of the drawings, it will be noted that the rod or bar 23 is secured at its ends to the tongue and is spaced therefrom by washers or spaced blocks 25 so that the front end of the bail 22 rides practically in a longitudinal slot of the draft-applying member of the machine.

To retain the scoop in position to take up a load or to support a load for transportation, I mount upon the tongue, near the front end thereof, a plurality of dogs which are adapted to engage and hold the front end of the draft bail 22. One of these dogs, 26, consists of a relatively long lever pivoted at its front end upon a pin or bolt 27 disposed transversely through the tongue 30 and passing through a longitudinal slot 28 in the tongue in which the said lever or dog is housed, the rear free end of the dog being somewhat widened, as shown at 29, to form practically a hook adapted to engage the front end of the draft bail as will be readily understood and as shown in Fig. 1. This lever or dog may rest upon the rod or bar 23 and is also partly supported by a second dog 30 which is disposed within the longitudinal slot 28 of the tongue below the said dog or lever 26 and is pivoted, as at 31, in rear of the pivot 27. The rear free end of the dog or lever 30 also projects downwardly, as shown at 32, to extend below the tongue and normally rest upon the bar or rod 23. This second smaller dog is equipped near its forward end with a lever 35 rigid with the side of the dog and having one end projecting above the tongue where it may be conveniently manipulated, the pivot of the dog being the fulcrum of the lever 35 and the two parts 30 and 35 constituting a bell crank lever.

It is thought the manner of using the described device will be readily understood. When a load is to be taken up, the bail 22 is engaged with the hook 29 so that the parts will be in the position shown in full lines in Fig. 1. The scraper is then drawn over the ground and the front edge of the bottom plate 1 will cut into the surface so that the surface soil will be taken up by the scoop. When the scoop has been filled, the lever 35 is rocked so as to lift the extremity 32 of the forward dog and the tractor is

then backed slightly so that the tongue 11 will move rearwardly relative to the bail 22, the weight of the load holding the scoop against rearward movement over the surface of the ground and thereby causing the front 70 end of the bail to ride forward to a position in advance of the holding extremity 32 of the dog 30. The rearward movement of the tongue will impart a slight rocking movement to the scoop so that it will assume the position shown in dotted lines in Fig. 1 and will then support the load in position to be moved to a point of discharge. When the front end of the bail has reached a point in advance of the dog 30, the lever 80 35 is released whereupon the dog will assume its normal position and will engage the front end of the bail so that if the scraper be then again drawn forward the loaded scoop will be drawn over the ground 85 without being discharged and without the scraper body taking into the surface of the soil. When the point of discharge has been reached, the lever 35 is again rocked and this time it should be rocked to the limit 90 of its movement so that the dog 30 will be raised to such an extent as to lift the larger dog or lever 26 out of the path of the bail. If the forward movement of the device be continued, the tongue will be drawn forward 95 while the weight of the load will hold the scraper body relatively stationary whereupon the bail will ride rearwardly upon the rod or bar 23. The relative rearward movement of the bail will continue until the front 100 end thereof reaches the rear spacer or washer 25 by which it will be arrested, but in the meanwhile the draft will be applied through the tongue to the pivot bolt 13 and a forward movement will be applied through said 105 bolt to the upper extremities of the standards 5 which will result in the scoop or scraper body being tilted and caused to rock upon the curved extremities of the members 16, as shown in Fig. 2, with the result that 110 the load will be discharged. The entire device is then drawn forward, while resting upon the rocker members 16, until it is clear of the discharged load, after which the parts are returned to the position shown in dotted 115 lines in Fig. 1 and drawn back to the place where excavating is to be done. The lever 35 is then rocked to raise the dog 30 clear of the bail whereupon the device is driven forward and, as soon as the bail has passed 120 in rear of the holding lip 32 of said dog, the lever is released so that the hook 29 of the dog 26 will be interposed in the path of the bail and will arrest the relative movement thereof and thereby restore the 125 scraper to its loading position.

In Figs. 7 and 8 I have shown a variation of the invention in which the tongue 40 is provided with a horizontal slot 41 in its rear end and the pivot bolt 42 plays in said slot 130

instead of being fixed in place as is the case with the pivot bolt 13 in the previously described form of the apparatus. To the ends of the bolt 42 are pivoted the rear ends of 5 links 43 which extend longitudinally of the tongue and have their front ends pivoted to a hand lever 44 fulcrumed upon the tongue. Preferably, the slot 28, shown in Fig. 5, will be elongated to receive the lever 44 10 which is equipped with a latch 45 cooperating with a segmental rack 46 secured upon the tongue. The scoop and the draft devices are of the same construction as in the form previously described.

15 The adjusting mechanism shown in Figs. 7 and 8 gives a more flexible control of the scoop and permits it to be adjusted without stopping.

My improved scraper is exceedingly simple in the construction and arrangement of its parts and may, therefore, be produced at a low cost. It is easily manipulated and is efficient in operation.

Having thus described the invention, what 25 is claimed as new is:

1. A scraper comprising a scoop, a draft tongue having a pivotal connection with the back of the scoop, a draft-applying device pivotally connected at its rear end with the 30 front of the scoop, and means on the tongue to engage the front end of said draft-applying device and hold it in a set position.

2. A scraper comprising a scoop, a draft tongue having a pivotal connection with the 35 back of the scoop, and a draft-applying device having its rear end pivotally connected with the front of the scoop and having its front end connected with and adjustable longitudinally of the draft tongue.

40 3. In a scraper, the combination of a scoop, a tongue having a pivotal connection with the back of the scoop, a draft-applying device pivotally attached to the front of the scoop and having a slidable connection with the tongue, and means on the tongue to engage said draft-applying device and hold it at a desired point of the tongue.

45 4. In a scraper, the combination of a scoop, a tongue having a pivotal connection with the back of the scoop, a bar secured to the under side of the tongue and extending longitudinally thereof, a draft-applying member pivotally attached to the front of the scoop and resting upon said bar, and a plurality of holding devices on the tongue near the front end of said bar to separately engage said draft-applying device.

50 5. In a scraper, the combination of a scoop, a tongue having a pivotal connection with the back of the scoop, a bail pivoted to

the front of the scoop and slidably supported on the tongue, and a plurality of dogs mounted on the tongue and each adapted to at times engage the bail.

6. In a scraper, the combination of a 65 scoop, a tongue having a pivotal connection with the back of the scoop, a bail pivoted to the front of the scoop and slidably supported on the tongue, a dog pivoted on the tongue and adapted to engage said bail, a 70 second dog pivoted on the tongue under the first dog and adapted to lift the same and also adapted to engage the bail, and means connected with the second-mentioned dog to operate the same. 75

7. In a scraper, the combination of a scoop, a draft tongue having a pivotal connection with the back of the scoop, a bail pivoted to the front of the scoop and having a slidable connection with the tongue, a dog 80 pivoted on the tongue and having its rear free end adapted to engage the bail, a second dog pivotally mounted on the tongue below the first-mentioned dog and having its free end adapted to engage the bail, the 85 pivot of the second dog being in rear of the pivot of the first dog and the two dogs being in the same vertical plane, and an operating lever pivoted upon the tongue concentric with the second dog and connected thereto. 90

8. In a scraper, the combination of a scoop, standards secured to the back of the scoop and having their lower portions extended under and secured to the scoop thereby forming runners, the upper ends of the 95 standards being projected above the scoop, a draft tongue pivotally mounted between the upper extremities of said standards, a draft-applying member pivoted to the front of the scoop, and means on the tongue to engage said draft-applying member. 100

9. In a scraper, the combination of a scoop comprising a bottom, sides and a back plate, a draft tongue having a pivotal connection with the back plate, extensible rockers secured to the back plate and to the sides of the scoop, a draft-applying device pivotally connected with the front of the scoop, and means on the tongue for engaging said draft-applying device. 105

10. A scraper comprising a scoop, a draft tongue having a pivotal connection with the back of the scoop, a draft-applying device connected with the front of the scoop, and means for adjusting the pivotal connection with the back of the scoop longitudinally of the tongue. 115

In testimony whereof I affix my signature.

NATHANIEL P. SLATE. [L.S.]
